UNITED STATES PATENT OFFICE.

EBERHARD SCHNEIDER, OF NEW YORK, N. Y.

PHOTOGRAPHIC-PRINTING MACHINE.

1,031,820.

Specification of Letters Patent.

Patented July 9, 1912.

Application filed December 3, 1909. Serial No. 531,154.

To all whom it may concern:

Be it known that I, EBERHARD SCHNEIDER, a citizen of the United States, residing at New York, in the county and State of New York, have invented certain new and useful Improvements in Photographic-Printing Machines, of which the following is a full, clear, and exact description.

This invention relates to photographic printing machines for printing positive moving picture films from negatives, and its chief object is to provide an improved machine for this purpose whereby the printing of the successive pictures or photographic images can be effected rapidly and with the utmost precision.

To this and other ends the invention consists in the novel features of construction and combinations of elements hereinafter described.

The invention is capable of embodiment in various forms, but I have selected for illustration and specific description herein only the form which at the present time is considered to exhibit the best mode of applying the invention in practice. This embodiment is shown in the annexed drawings, and referring now thereto, Figure 1 shows the complete machine in side elevation. Fig. 2 is a front view with the front of the casing removed, to show the film-feeding mechanism. Fig. 3 is a rear view. Fig. 4 is a vertical section, on line IV—IV of Fig. 2. Figs. 5 and 6 are detail sectional views, on substantially the same plane as Fig. 4, but with various parts of the mechanism omitted. Fig. 7 is a detail view of an element of the mechanism employed to advance and retract the pins by which the forward feed of the films is effected. Fig. 8 is a detail horizontal section on line VIII—VIII of Fig. 3, showing the position of the feeding pins with respect to the films while the latter are being fed forward.

The feeding and exposing devices are conveniently mounted in or upon a suitable casing 1, on top of which is a standard 2 carrying an upper reel or spool 3 from which the unexposed positive film 3^a is drawn, and a lower reel or spool 4 from which the negative film 4^a is drawn. Instead of employing means for maintaining a loop of film between the supply reels and the devices which effect the step-by-step advance of the film past the point of exposure,

I prefer to have the films slightly taut and for that purpose provide a pair of tensioning idlers 5, 6, on arms 7, 8, pivoted to the standard 2. The arms are drawn yieldingly 69 apart by two light springs 9, 10, and the films pass under the lower idle roller and over the upper, as shown in Figs. 1 and 4. The rollers are preferably covered with velvet or equivalent material so as to take 65 a light grip on the films without injuring their delicate surfaces.

In the front wall of the casing is a light aperture 11, encircled by a forwardly extending hood 12. The machine is intended 70 to be used in a dark room, and is arranged with this hood in register with a window or opening in the dark room wall. Outside of the dark room is the source of light, for example an incandescent electric lamp 13, 75 which may be conveniently carried on a bar 14 slidably mounted on the base 15 of the machine and entering through a suitable aperture in the dark room wall, not shown. The effective intensity of the light 80 can therefore be varied as desired by advancing or retracting the adjustable support 14 to vary the distance of the source of light from the point of exposure.

Extending from the light aperture 11 to 85 the rear wall 16 of the casing is a rectangular chamber 17 in which is mounted the shutter for cutting off the light except during the periods of exposure. The preferred form of shutter is of the "eyelid" type, 90 comprising two plates or lids 18, 19, pivoted at the top and bottom of the chamber between two triangular side plates one of which is shown at 20 in Fig. 6. The pivots or rods 21, 22, to which the shutter lids are 95 attached by their rear ends, are provided with fingers 23, 24, at one side of the chamber 17. These fingers cross, as shown, and are engaged in the rear by a pin 25 extending laterally from an operating member 100 in the form of a vertical rod 26, and in front by a similar pin 27 on a spring arm 28 mounted on said rod. The latter is carried by a horizontal lever 29 (Fig. 2) fulcrumed on a vertical guide-rod 30 at the 105 opposite side of the machine. A spring 31, fastened to the front wall of the casing, bears against the rod 26 and urges the same rearwardly, thereby causing the pin 27 to swing the fingers 23, 24, to the rear, closing 110 the shutter lids down upon the triangular side plates and cutting off the light. The

spring 31 is made strong enough to effect the closing of the shutter with absolute certainty, and the spring 28, on which the closing pin 27 is carried, by yielding permits the rod 26 to move rearwardly past the position at which the shutter is closed. At proper intervals the rod 26 is advanced by a cam 32 on a rotating shaft 33, as more fully described hereinafter. This movement of the rod causes the pin 25 to swing the fingers 23, 24, forward, thereby opening the shutter.

The shutter and its actuating mechanism, described above, are simple in construction but are thoroughly effective for their purpose and operate with the utmost precision.

From the tensioning roller 5 the negative film passes under and the positive over a clamping gate or bar 34 hinged to the rear wall of the machine at one side thereof and carrying a pair of flat springs 35 which bear on the sides of the negative film and hold the same against the wall of the casing with light pressure so as to prevent any looseness or slack in the film below the clamp. The clamping bar is held in operative position by a button 36 engaging its free end.

From the clamp 34 the films pass the point of exposure, at the rear end of the chamber 17, in which is mounted a rectangular frame or mask 36 the internal dimensions of which are exactly those which the photographic image on the position film is to have. Immediately behind the mask 36 is a film supporting plate 38, preferably of polished ruby glass, the forward surface of which is cylindrical and of any suitable curvature. This plate is mounted in a support or carrier 39, hinged at one side of the machine and held in its forward position by a spring-pressed bolt or latch 40. The mask 36 has its rear face concaved, as shown, in conformity with the curvature of the back plate 38, and the parts are so proportioned as to leave between the two a space equal to three thicknesses of the film. A space equal to two thicknesses would ordinarily be sufficient, but sometimes a film must be spliced, and provision is therefore made for the extra thickness. Above and below the mask or frame 36 are two idle rollers 41, 42, journaled in the sides of the chamber 17. The rollers and mask are preferably arranged as shown in Fig. 4, with the rollers tangent both to the curved surface (produced) of the mask and to the flat surface of the rear wall 43 of the machine, above and below the light chamber 17. This arrangement is advantageous in avoiding sharp bends in the film, as the bends which it undergoes in passing over the rollers are no sharper than the curvature of the rollers themselves. The ruby glass back plate or film support is an important feature, as its capacity of absorbing actinic rays practi-

cally overcomes fogging and halation of the positive film by light striking it from the rear.

In passing over the back plate 38 the curved surface thereof bulges the films forward and thereby brings the positive film into close and even contact with the negative film throughout their entire engaging surfaces, and thus insures the sharpest possible definition in the printing.

The step-by-step film-feeding and the shutter-operating mechanism, is arranged in the casing 1 below the light chamber 17, and is actuated by the shaft 33, before mentioned, which is rotated continuously by any suitable means, as for example a crank disk 44. The feed of the films is directly effected by a vertically reciprocating fork 45 the arms of which are spaced apart by a distance equal to the space between the rows of sprocket holes at the edges of the films, and each arm is provided with one or more pins 46, preferably two, to project through the sprocket holes and fit the same accurately. The holes in the positive and negative films are thus brought into register and the films accurately justified. These pins project through vertical slots 47 in the rear wall 16 and beyond the films extend into vertical grooves 48 in the forward face 90 of a gate or plate 49 hinged at the side of the machine. The gate serves to hold the films close to the rear wall, and is held in operative position by a spring bolt 50 similar to bolt 40.

The film-feeding fork 45 is carried at the upper end of a vertical supporting member 51 mounted at its lower end on a transverse pin or rod 52 one end of which extends into a vertical slotted guide 53 while the other end extends into the lower end of a rod 54 mounted to reciprocate vertically in suitable bearings 54, 55. On the side of the rod 55 next to the driving shaft 33 is a plate 56 (Fig. 7) having a transverse slot 57, into which extends a crank pin 58 carried by a crank 59 on the end of said shaft. The path of the center of the crank pin is indicated by the broken-line circle 60, Fig. 7, and the parts are so proportioned that the reciprocatory travel of the rod 53 and fork 45, produced by the agency of the slotted member 56 and the crank 59, will be just equal to the distance between the centers of successive pictures on the films.

In addition to its vertical movement the fork 45 is capable of limited oscillation about the pin 52 as a pivot, but is urged rearwardly by a coil spring 61 mounted on the pin 52 and by a vertical lever 62 fulcrumed at its lower end and pressed rearwardly by a flat spring 63. At the top the lever carries an antifriction roller 64 bearing on the fork-supporting bar 51. The forward swing of the fork 45, to carry the

pins 46 out of engagement with the film-holes at the completion of the downward feeding movement of the pins is effected by a cam 65 (Fig. 5) on the driving shaft 33, 5 the cam being of sufficient radial and angular extent to hold the pins out of engagement with the films only during the upward movement of the pins.

Beginning with the pins in the position of 10 Fig. 5, and with the cam rotating in the direction of the arrow adjacent thereto, the cam first releases the fork-supporting member 51, whereupon the spring 61 and lever 62 throw the member 51 and pins 46 rearward, bringing the latter into engagement 15 with the films, as in Fig. 4. At this time the crank 59, at its uppermost position, begins to descend, drawing down the rod 53, member 51, fork 45 and pins 46, as previously described, and producing a downward movement of the two films through a space equal to the width of a picture. During this movement the shutter in the shutter chamber 17 is closed, but on completion of 20 the movement the cam 32 on the driving shaft engages the shutter-operating member 26, throwing the same forward and opening the shutter as in Fig. 6, in the manner before explained; it being understood, of course, that, the speed of the driving shaft being constant, the period of time during 25 which the shutter is open and the films are exposed to the light depends upon the design of the shutter-operating cam 32. As the cam moves out of engagement with the member 26 the spring 31 moves the said member backward and closes the shutter. In the meantime, while the shutter is open and the fork 45 is at its lowermost position 30 40 the cam 65 again comes into engagement with the fork-supporting member 51 and swings the same forward, carrying the film-feeding pins out of the film-holes; whereupon the ascending movement of the crank 59 raises the pin-fork again to the position shown in Fig. 5.

Since the films are exposed to the light while the feeding pins 46 are disengaged, any displacement of either film with respect to the other, as might occur if the two were allowed to hang loosely below the point of exposure, would impair the definition of the positive. To eliminate the possibility of such displacement a pressure 55 clutch member 66 is provided, (see Fig. 5), in the form of a long narrow plate, working in a similarly shaped aperture in the rear wall 43 immediately in front of the gate 49, and adapted to press the two films together 60 against the gate. The clutch member is suspended in place by a pin 67 projecting from its forward face and extending loosely into an actuating plate 68, suspended loosely from its upper end on a screw 69 which 65 affords a pivotal support for the plate. In

front of the latter, on the shaft 33, is a cam 70, arranged to engage the actuating plate 68 and hence carry the clutch member 66 back against the films. This cam is on the side of the shaft opposite to the cam 65, which withdraws the pins 46 from the film-holes, and the angular extent of the clutch cam is such that it will cause the clutch to engage the film a little in advance of the withdrawal of the pins and will keep the film engaged until the pins are ready to begin their downward (and feeding) movement. At this time the clutch cam moves out of engagement with the actuating plate and allows the clutch to swing forward of its own weight and release the film. 70

It is of course desirable that the films suffer no lateral displacement such as would bring the photographic images too near or cause them to overlap the sprocket holes, and to prevent such displacement the back wall 43 is provided with two guides 71 on opposite sides of the path of the films, forming a channel just wide enough to permit the films to pass easily. It is also desirable that the pictures on the negative film be in accurate vertical register with the mask or frame 36, and to permit adjustment with respect to the mask whenever necessary in order to maintain such register all the film-feeding devices, including the shaft 33, which are located in the lower part of the casing below the shutter chamber 17, are mounted on a plate or carrier 72. The latter is capable of vertical adjustment on two rods or guides one of which is the rod 30 to which the shutter-operating member 29 is pivoted. The other is shown at 73, and is rotatably mounted in a bearing 74 on the rear wall 43. The lower end of the rod 73 is enlarged, as at 75, to form a supporting shoulder for the carrier 72, and screws into a lug 76 below said carrier. At its top the rod has a milled head or knob 77, by which it may be screwed into or out of the lug mentioned. This vertical movement of the adjusting rod of course produces a corresponding adjustment of the film-feeding devices; and it is clear that if the feed pins are in engagement with the film, or films as the case may be, the latter will be correspondingly shifted with respect to the mask 36. The shutter should be open during this operation, so that the operator, looking through the glass film support 38, 105 can make the adjustment accurately; but, as will be remembered, the shutter is normally closed while the feed-pins are in their rearward position and in engagement with the films. Means for opening the shutter whenever desired are provided, as for example a plunger or rod 78, normally retracted by a coil spring 79 and having its forward end close to or in contact with the shutter-operating member 26, as shown in Fig. 4. 110 120 125 130

Forward movement of this plunger, under the pressure of the finger, advances the member 26, which opens the shutter as previously described. The operator can then observe the position of the picture and effect such adjustment by means of the adjusting rod 73 as may be necessary.

As before stated, the feeding pins 46 are shaped to fit accurately the holes in the sides 10 of the two films, with the result that if the films are not accurately positioned with respect to each other one or the other or both will be shifted slightly as the pins move into the holes. Assuming that the spacing of the 15 holes in the negative is too short, it is evident that any inaccuracy of its position relative to the positive should be corrected by adjustment or shifting of the negative instead of the positive. But since only the 20 negative film is held by the springs 35 on the tension clamp 34 at the top of the casing, it may happen that the positive film may move by adhesion to the negative and hence cause inaccurate spacing of the images on 25 the former. To prevent such occurrence a separate clamp may be provided for the positive, so that the same will be held independently of the negative while the feed pins are entering the sprocket holes. A 30 clamp for this purpose is shown at 80, Figs. 3 and 4, pivoted to the clamp 34 and held in operative position by a latch or button 81. The positive may then be passed between the 35 two clamps, in which case it is pressed lightly against the back of clamp 34 by two springs 82 carried by the other. The force of these springs may be made sufficient to prevent any movement of the positive film by the feed pins except when the negative is 40 accurately positioned with respect to the pins.

After leaving the pressure clutch 66 the 45 films may pass through a slot 83 in the base of the machine into a receptacle or box 84, where they may be received upon a suitable 50 take-up reel (not shown) with or without the maintenance of the usual loop, or they may pass to the rear below the gate 49, as may be most convenient under the circumstances.

As the operation of the machine has been explained in connection with the description of the instrumentalities composing the apparatus further explanation in that direction is deemed unnecessary. Suffice it to say that extensive use of the machine illustrated has shown it to be thoroughly effective for its purpose, the printing being performed rapidly and with the utmost certainty and precision. At the same time the mechanism is not complicated, and the parts 60 can be substantially and durably constructed.

It is to be understood that the invention is not limited to the precise form herein specifically illustrated and described, but is ca-

pable of other embodiments without departure from its proper spirit and scope.

What I claim is:

1. In a photographic printing machine of the kind described having an exposure point, the combination of a support on one side of the exposure point having means for frictionally engaging a film, a second support having means for frictionally engaging another film between the first and second supports, and means on the other side of the exposure point for feeding both films step by step past the exposure point. 70 75

2. In a photographic printing machine of the kind described, the combination of a casting having a wall provided with a light aperture, a spring clamp hinged to the wall on one side of said aperture to engage a film with yielding pressure, a second spring clamp hinged to the first to engage another film with yielding pressure, and means on the other side of the light aperture for feeding both films step by step. 80 85

3. In a photographic printing machine of the kind described, the combination of a shutter comprising pivoted plates, crossed operating arms connected to the plates, actuating means engaging the arms on opposite sides at their crossing point, step-by-step film-feeding mechanism, and devices operated by the film-feeding mechanism for intermittently actuating said means. 90 95

4. In a photographic printing machine of the kind described, having a light aperture, a film support comprising a cylindrically curved plate of ruby glass arranged back of the light and arranged to bulge the film toward said aperture. 100

5. In a photographic printing machine of the kind described having a light aperture, 105 in combination, a film support comprising a cylindrically convex plate of ruby glass arranged back of the light aperture and adapted to bulge the film toward said aperture, and a centrally open frame carrying the 110 film support and permitting inspection of the film from the rear.

6. In a photographic printing machine of the kind described, the combination of a wall over which the films pass, said wall 115 being provided with an aperture for exposing the films to light, a cylindrically curved mask-frame arranged in said aperture, and providing recesses on opposite sides of the mask-frame between the same and the edges 120 of said aperture, means back of the mask-frame for giving the films a corresponding curvature, and rollers over which the films pass in their movement across the said opening, said rollers being mounted in said recesses on opposite sides of the mask-frame and tangent both to the curvature of the mask frame and to the surface of said wall. 125

7. In a photographic printing machine of the kind described having a light aperture, 130

the combination of mechanism for feeding the films step-by-step past the light aperture, a carrier on which said mechanism is mounted, and means for adjusting the carrier to vary the position of the feeding mechanism with respect to the light aperture.

8. In a photographic printing machine of the kind described, a wall having a light 10 aperture, parallel guide rods in a plane parallel to the plane of the light aperture, a plate adjustably mounted on the guide rods, and step-by-step film-feeding mechanism mounted on the plate.

15 9. In a photographic printing machine of the kind described, the combination of a vertical wall having a light aperture, vertical guide rods adjacent to the wall, a carrier adjustably mounted on the guide rods, step-by- 20 step film-feeding mechanism mounted on the carrier, and means connected to one of the guide rods and actuated by rotation of the same to adjust the carrier on the rods.

10. In a photographic printing machine 25 of the kind described, the combination of a casing having a vertical wall provided with an opening for the passage of light, step-by-step film-feeding mechanism within the casing below the said opening, a vertically adjust- 30 able carrier on which said mechanism is mounted, and a screw rod connected with the carrier to adjust the same and extending upwardly to the exterior of the casing.

11. In a photographic printing machine 35 of the kind described, the combination of a wall over which the films pass, said wall being provided with an opening for exposing the films to light, film-feeding mechanism alternately engaging and releasing the films 40 on one side of the exposure opening, a clutch plate mounted in said wall on the same side of the exposure opening, and means actuating the clutch plate to hold the films stationary while they are disengaged from the 45 feeding mechanism.

12. In a photographic printing machine of the kind described, the combination of a vertically extending member, a vertically reciprocating support on which the lower end 50 of said member is pivoted, a film-engaging device carried on the upper end of said member, a cam arranged to oscillate said member in one direction, yielding means en-

gaging the member to oscillate the same in the opposite direction, a shaft on which the 55 cam is mounted, and means actuated by the shaft for reciprocating said support.

13. In a photographic printing machine of the kind described, the combination of a vertical wall having an opening for exposing the films to light and provided with a pair of vertical slots below said opening, a fork having film-engaging pins co-acting with the slots, a pivoted supporting member for the fork, means for oscillating the supporting member to advance and retract the fork, whereby to alternately engage and release the films and means for reciprocating the supporting member vertically.

14. In a photographic printing machine 70 of the kind described, the combination of a reciprocating film-feeding member, a pivoted support therefor, a reciprocating rod connected with said member to actuate the same, a plate carried by the rod and provided with a transverse slot, a driving shaft having a crank engaging the said slot whereby the rotation of the shaft will reciprocate the film-feeding member, and means for swinging the film-feeding member on its 75 pivoted support to engage and release the film.

15. In a photographic printing machine of the kind described, the combination of an oscillatory film-feeding member, yielding 85 means urging the member in one direction, and a cam for swinging the member in the opposite direction.

16. In a photographic printing machine of the kind described, the combination of a 90 fork having pins adapted to engage film sprocket-holes, a supporting member for the fork pivoted to oscillate forwardly and rearwardly, mechanism for oscillating and reciprocating the supporting member, a movable clutch plate adapted to engage the films, and means for actuating the clutch plate to cause the same to engage the film during the forward oscillation of the supporting member and fork.

In testimony whereof I affix my signature in the presence of two subscribing witnesses.

EBERHARD SCHNEIDER.
